UNITED STATES PATENT OFFICE.

SAMUEL GERTZ, OF CLEVELAND, OHIO, ASSIGNOR TO THE C. O. BARTLETT & SNOW COMPANY, OF CLEVELAND, OHIO, A CORPORATION OF OHIO.

DRYING MECHANISM AND THE LIKE.

Application filed October 26, 1922. Serial No. 597,150.

The present improvements, relating as indicated to drying mechanism, have more particular regard to so-called rotary cylinder driers, but are equally applicable to 5 kilns or retorts of such rotary cylinder type. In driers of the type in question, the rotary cylinder is usually supported at a slight incline in a furnace chamber, the gases from the furnace coming into contact only with the outside of the cylinder and the vapors or gases evolved inside the cylinder being withdrawn through an opening at either end of the latter. A serious difficulty, however, arises in the operation of such a drier where 10 finely comminuted or powdered materials are being treated due to the dust created by the passage of the vapors or gases through the cylinder in the usual longitudinal direction. The velocity of such current, at 15 least at certain points in the cylinder, becomes sufficient to carry off a measurable quantity of the material, which must be recovered, if serious loss is to be avoided, quite aside from the nuisance which such dust 20 constitutes. A similar situation is of course presented where a vapor of any kind or a gas is given off from the material being treated in a rotary cylindrical kiln or retort and such vapor or gas requires to be 25 educted.

The object of the present invention, accordingly, is the provision of means for use in such rotary cylinder driers, kilns or retorts, whereby part or all of the moisture 30 or other vapors or gases, given off from the material being treated, may be withdrawn transversely of the cylinder instead of in the usual longitudinal direction, thus avoiding the creation in any part of the cylinder of a current of such velocity and direction as will carry with it dust from the material. Another object is to provide for 35 the regulation of the rate of withdrawal to suit the needs of a particular operation.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but

one of various mechanical forms in which the principle of the invention may be used.

In said annexed drawing:-

Fig. 1 is a longitudinal central section of a rotary cylinder drier wherein my present improvements have been incorporated; Fig. 2 is a transverse section of the drier cylinder at a point intermediate of its ends; Fig. 3 is a transverse section, on a larger scale, of a duct within such drier cylinder that forms a feature of the present invention; Fig. 4 is a broken longitudinal section of such duct, the plane of the section being indicated by the line 4-4, Fig. 3; and Figs. 5, 6 and 7 are sectional views, similar to that of Fig. 3, but showing modified forms of the duct in question.

As shown in Fig. 1, the rotary cylinder 70 that constitutes the drying chamber proper is of usual elongated form, being rotatably mounted on suitable bearings 2 and 3 adjacent its respective ends. Such cylinder inclines slightly from the horizontal so that material supplied to its interior at the higher end, e. g. the left, as shown in Fig. 1, will gradually move under the influence of gravity towards the opposite end as the cylinder is rotated. Any suitable form of 80 feed device may of course be employed to supply the material to such first mentioned end of the cylinder, a screw conveyor 4 being shown by way of illustration. It will be understood that save for such feed device, the end in question is otherwise closed, as by means of a fixed head 5, while the opposite end is connected with a closed chamber 6 adapted to receive the material as it is discharged from such end. For rotating the cylinder an annular gear 7 is 85 exteriorly attached thereto, preferably at the front end, such gear being driven from a suitable pinion 8 as need not be further described.

Substantially the entire portion of the cylinder lying between the bearings 2 and 3 is located within the walls of a heating chamber 10, the detailed construction of which likewise is not of present interest, 90 such chamber being shown, by way of illustration, as being heated by means of a grate 11 located at the end adjacent the forward or upper end of the cylinder, while a flue

12 connected with the opposite end of the chamber serves to conduct the smoke and gases of combustion away therefrom after such gases have circulated around the cylinder. A series of longitudinally extending ribs 13, secured to the inner wall of the cylinder, is provided to keep the material from collecting in the bottom.

Extending longitudinally of a cylinder, 10 preferably all of its length, and preferably lying in the upper portion thereof, is a pipe or duct 14. One end of this duct is supported in the stationary head 5 at the forward end of the cylinder, while the other 15 end of said duct is supported in the housing 6 at its lower end of the cylinder when said duct extends the entire length of the cylinder as shown in Fig. 1. Such duct, in other words, is supported independently of the 20 cylinder and is stationary relatively thereto. A fan 15, or equivalent means for producing the suction within said duct 14, is connected with the forward end of the latter and such duct is provided in that portion 25 which lies within the cylinder with a series of openings 16. The suction produced by fan 15, as aforesaid, will accordingly be effective to draw vapors or gases from the interior of the cylinder through such openings 16 into the duct 14 and thence discharge them.

The number of openings, as well as the spacing thereof, may be varied to suit the particular use to which the drier is being 35 put. Furthermore, means may be provided to vary the size of the openings, either the size of all such openings simultaneously or of different openings or group of openings independently of the others. Preferably the 40 duct 14 will be of the rectangular cross-section shown in Figs. 2 and 3, with one of its longer dimensions disposed vertically, and the openings 16 will be formed in the downwardly directed sides of the duct. For the 45 purpose of regulating such openings, slides 17 will be secured against the inner faces of the same walls, respectively, such slides having openings corresponding with the openings 16 so that the latter may be left entirely unobstructed in one position of the 50 slides, but by moving the latter longitudinally of the walls against which they rest, the openings 16 may be more or less completely closed. Any suitable means may be, 55 of course, provided for operating the slides, the means shown comprising a handled rod 18 at the forward end of the duct that is attached to each one of the slides.

The form of the duct 16 may be varied 60 without departing from the spirit of the invention. Thus, in Fig. 5, I show a duct 19 of similar rectangular cross-section and similarly disposed. However, the upper walls of the duct are formed with overhanging 65 extensions 20 that serve to protect the open-

ings 21 in the lower walls against the entrance of dust or fine material from the cylinder. In Fig. 6, a duct 22 of circular cross-section is shown, the openings 23 therein being controlled by means of a rotatable closure 24 fitted around the duct and adapted to be rotated through a pinion 25 inter- 70

geared therewith. Fig. 7 shows still another form, the upper portion of the duct 26 being curved in cross-section, while the lower portion is angular so as to present two inclined walls similar to the lower walls of the first described duct 16. As before, the openings 27 will preferably be formed in such inclined walls since such dust as is produced in the rotation of the cylinder will have that much less tendency to enter the duct. In any event, the dusting produced in the operation of the drier will be greatly lessened due to the reduction in the velocity of the currents 80 drawn through the several openings in the duct 16, or its equivalent, as compared with the case where the entire current of air or gas is drawn lengthwise through the cylinder. Such currents as are produced will 85 furthermore be transverse of the axis of the cylinder and by shielding the openings in the duct, the dust will in large part be returned to the body of material in the cylinder instead of being drawn off. Finally, 90 by providing different sizing or spacing of the openings in the duct lengthwise thereof, as well as by providing for the adjustment of the size of such openings, the rate at 95 which the gases are withdrawn from different portions of the cylinder's interior may be exactly regulated to suit conditions. Thus, obviously where the operation is a simple drying one, moisture or water vapor being expelled from the material, the volume of such vapor will ordinarily be much 100 greater in the initial stage of drying, i. e., at the upper end of the cylinder, than in the final stage where the material is heated most highly in order to drive off the last 105 traces of moisture. By means of my improved construction, I am enabled to vary the suction in such different portions of the cylinder so as to take care of the moisture present, and a very small amount of suction 110 may be found sufficient in the final stage which is the one where dusting is, of course, most liable to occur.

In order to prevent condensation of moisture in or on the duct, the latter may be suitably insulated, as for example with asbestos or magnesia. With the same object in view, i. e., the prevention of condensation, a certain amount of preheated air may be introduced into the duct and mixed with the vapors, thereby maintaining the latter at a temperature above that at which condensation would occur. The source from which such preheated air is obtained is a matter of indifference, but, as shown in Fig. 120 125 130

1, an extension 28 connected with the lower end of the duct 14 and passing through the corresponding end of the furnace chamber will act as a heater for any air drawn 5 through such extension. A damper 29 in such duct 28 serves to regulate the amount of preheated air thus admitted to the duct 14.

Other modes of applying the principle of 10 my invention may be employed instead of the one explained, change being made as regards the mechanism herein disclosed, provided the steps or means stated by any of 15 the following claims or the equivalent of such stated steps or means be employed.

I therefore particularly point out and distinctly claim as my invention:

1. In a method of abstracting the vapors or gases arising from material being heated 20 in a rotary cylinder, the step which consists in withdrawing part or all of such vapors or gases transversely of the axis of such cylinder and in different amounts at different points longitudinally of such axis.

2. In a method of abstracting the vapors or gases arising from material being heated in a rotary cylinder, the steps which consist in withdrawing part or all of such vapors or 30 gases transversely of the axis of such cylinder, and supplying a current of preheated air into which such vapors or gases are thus withdrawn.

3. In a method of abstracting the vapors or gases arising from material being heated 35 in a rotary cylinder, the steps which consist in withdrawing part or all of such vapors or gases transversely of the axis of such cylinder and in different amounts at different points longitudinally of such axis, and supplying a current of preheated air into which such vapors or gases are thus withdrawn.

4. In mechanism of the character described, the combination of a heating chamber; a rotary cylinder located therein; and 45 means for abstracting the vapors or gases that arise from material being treated in said cylinder, said means including a relatively stationary duct extending longitudinally of said cylinder adjacent the upper 50 wall thereof and provided with a series of shielded spaced openings.

5. In mechanism of the character described, the combination of a heating chamber; a rotary cylinder located therein; and

means for abstracting the vapors or gases 55 that arise from material being treated in said cylinder, said means including a relatively stationary duct extending longitudinally of said cylinder adjacent the upper wall thereof and provided with a series of 60 spaced, downwardly directed openings.

6. In mechanism of the character described, the combination of a heating chamber; a rotary cylinder located therein; and means for abstracting the vapors or gases 65 that arise from material being treated in said cylinder, said means including a relatively stationary duct extending longitudinally of said cylinder adjacent the upper wall thereof and provided with a series of 70 spaced openings of adjustable size.

7. In mechanism of the character described, the combination of a heating chamber; a rotary cylinder located therein; and means for abstracting the vapors or gases 75 that arise from material being treated in said cylinder, said means including a relatively stationary duct extending longitudinally of said cylinder adjacent the upper wall thereof, the under side of said duct comprising angularly related walls each provided with a series of spaced openings.

8. In mechanism of the character described, the combination of a heating chamber; a rotary cylinder located therein; and 85 means for abstracting the vapors or gases that arise from material being treated in said cylinder, said means including a relatively stationary duct extending longitudinally of said cylinder adjacent the upper 90 wall thereof, the under side of said duct comprising angularly related walls each provided with a series of spaced openings, and a slide co-operative with each such wall adapted to adjust the size of the openings 95 therein.

9. In mechanism of the character described, the combination of a heating chamber; a rotary cylinder located therein; and means for abstracting the vapors or gases 100 that arise from material being treated in said cylinder, said means including a relatively stationary duct extending into said cylinder, and connections for supplying pre-heated gases to said duct.

Signed by me, this 23rd day of October, 1922.

SAMUEL GERTZ,
